UNITED STATES PATENT OFFICE.

MARTIN R. BRUNER, OF WAPAKONETA, OHIO.

METALLIC WHEEL.

1,009,642.

Specification of Letters Patent. Patented Nov. 21, 1911.

Application filed April 16, 1909. Serial No. 490,400.

To all whom it may concern:

Be it known that I, MARTIN R. BRUNER, a citizen of the United States, residing at Wapakoneta, in the county of Auglaize and State of Ohio, have invented a new and useful Metallic Wheel; and I do hereby declare the following to be a full, clear, and exact description of the invention, such as will enable others skilled in the art to which it appertains to make and use the same.

This invention belongs to the art of metallic wheel constructions for vehicles and agricultural implements, and it particularly pertains to a metallic wheel in which the spokes thereof are composed of a single piece of sheet metal which is depressed from opposite sides so as to form the spokes. The forming of the spokes in this manner leaves annular rings, one adjacent to the hub of the wheel, to which the two sections of the hub are clamped, and an outer annular ring, to which the two sections of the rim of the wheel are clamped or riveted.

The main object of the invention is to provide a wheel of this kind which is simple and efficient in construction, durable and practical in use thereof, combined with heretofore named novel features.

This invention comprises further objects and combinations of elements which will be hereinafter more fully described, shown in the accompanying drawings, and the novel features thereof will be pointed out by the appended claims.

The features and elements and the arrangement thereof, for accomplishing the objects of this device or apparatus, may be changed and varied, that is to say, in an actual reduction to practice, the understanding, however, is that the changes and variations accruing from said reduction to practice are comprehended by the appended claim.

In the drawings:—Figure 1 is a side elevation of a metallic wheel embodying the features of the invention. Fig. 2 is a sectional view on line 2—2 of Fig. 1, clearly illustrating the details of the invention. Fig. 3 is a detail sectional view on an enlarged scale, clearly defining the shoulders of the spokes, serving to withstand the strain on the periphery of the disk.

In regard to the annexed drawings, 1 designates a single piece of sheet metal, which is provided with a central opening 2, as shown clearly in Fig. 3. This piece of

sheet metal is depressed from opposite sides, by any suitable means, but which is not shown, for the reason that it forms no part of the present invention. The pressing of the sheet metal from opposite sides forms outwardly tapering spokes 4 of the wheel, which extend radially from the central opening. The forming of the spokes in this manner materially strengthens the same, and the entire wheel. These spokes do not quite extend to the periphery of this piece of sheet metal, and for this reason, there remains an unobstructed annular surface and periphery 5, to which the two annular sections 6 of the rim 7 of the wheel are bolted or riveted, or otherwise secured, as shown at 8. The spokes 4 taper outwardly from the hub, and the outer ends of the spokes serve as shoulders 4^b, terminating short of the sections or annular rings 6 to withstand the strain on the periphery of the disk, and to act as abutments for the rings or sections 6. These sections or rings 6 of the rim of the wheel are annularly grooved, as indicated by the numeral 9, and when secured to the unobstructed surface of the sheet metal, there is an annular groove 10 formed about the entire rim of the wheel, which annular groove 10 is semi-circular in cross section.

The hub 11 of the wheel is composed of three members 12, 13 and 14; the member 12 (which is the hub proper of the wheel) is provided with a threaded portion 15, and a shoulder 16, which is formed in the shape of convolutions 17, so as to fit properly and adjacent to the said spokes. The member 13 is in the form of a washer, having convolutions 18 to fit the spokes, and opposite the shouldered portion of the member 12. When the washer or member 13 is securely clamped adjacent to the spokes, by means of the member or nut 14, end wise movement or lateral movement of the hub portion proper or the member 13, is materially prevented, as will be clearly apparent on examining the drawings. The member or nut 14 is provided with threads to engage the threaded portion 15 of the member 12, as shown. The hub portion proper or member 12 is provided with a cylindrical bore 19, so as to fit the spindle of an axle.

By forming spokes or convolutions of metallic wheels in this manner, strength, durability and rigidity is afforded, as will be clearly evident.

Upon referring to Fig. 4 it would be ob-

served that the metal between the spokes or convolutions is removed, as indicated by the characters 4*.

From the foregoing, the essential features, elements and the operation of the device, together with the simplicity thereof, will be clearly apparent.

Having thus fully described the invention, what is claimed as new and useful, 10 is:—

In a wheel having a hub provided with a threaded portion having an annular convoluted plate, the hub having a convoluted washer fitting the threaded portion and provided with a nut threaded on the threaded portion against the washer; the wheel comprising a single sheet metal plain disk through which the threaded portion pene- 15

trates; annular rings secured on each face of the disk adjacent the periphery thereof, and 20 constructed to form an annular groove; the disk having spokes pressed in opposite directions, therein, and tapering outwardly from the hub, the outer ends of the spokes serving as shoulders terminating short of 25 the annular rings to withstand the strain on the periphery of the disk, and to act as abutments for the rings.

In testimony whereof I have signed my name to this specification in the presence of 30 two subscribing witnesses.

MARTIN R. BRUNER.
